UNITED STATES PATENT OFFICE.

CAESAR NEUMANN, OF NEW YORK, N. Y.

MACHINE FOR MAKING HOOP-SKIRTS.

Specification of Letters Patent No. 28,893, dated June 26, 1860.

To all whom it may concern:

Be it known that I, CAESAR NEUMANN, of the city, county, and State of New York, have invented certain new and useful Improvements in Machinery for the Manufacture of Skeleton Skirts; and I do hereby declare the following to be a full, clear, and exact description thereof, referring to the accompanying drawing, in which—

10 Figure 1 is a side elevation. Fig. 2 is a vertical section. Fig. 3 is a plan of the twist gearing. Fig. 4 is a plan of the twist apparatus. Fig. 5, is a sectional plan showing the base and elevating drum *d*. Fig. 6 15 enlarged view of the twist apparatus and guide for inserting the hoop. Fig. 7, top view of former and apparatus connected therewith in position to receive the spring.

My improvements consist of the manner 20 of holding and presenting the cords, the guides for inserting the spring hoops, the constructing of the twisting apparatus, and apparatus for elevating and lowering the former.

25 The construction is as follows: On a proper base I erect an iron standard *a* consisting of a round bar, on this vertical standard *a* I place a large spur gear wheel *b* which runs near the base, as clearly seen in 30 the elevation and section Figs. 1 and 2. Above the wheel *b* the former *c* is put upon the standard *a*. This former consists of a series of stout iron wires or bars *c'* bent into the form of a skirt with these lower ends 35 brought inward. The upper and lower ends of these wires *c'* are properly affixed to circular metal flanches *c*, having bosses at their centers through which the standard *a* passes. There is a pulley *a'* at the top of the standard, 40 and a cord *c''* attached by one end to the upper flanch *c* passes up over said pulley and thence down to a small drum *d* below, which drum is on a horizontal shaft that extends out beyond the periphering of the 45 gear wheel *b* and former, at which point it bears a worm wheel *d'* into which a worm on an upright driving shaft *e* gears, said upright shaft being operated by a level gear *f* connecting it with a hand crank at *f*. The gearing of the worm wheel can be coupled or uncoupled by a sliding outer bearing, and when 50 out of gear it can be turned by the hand wheel *d''* on the end of the shaft so as to quickly raise or lower the former by winding or unwinding the cord *c''* around the drum *d*. When the worm wheel is in gear

the former is slowly raised, so as properly to lay the cord from the twisters hereafter described.

The twisting apparatus is formed as follows: Sliding pieces *h* are made so as to traverse the rods of the former as it is raised as before described, the sliding pieces *h* form the upper bearings of a series of twisting rods or shafts *i*, an enlarged view 60 of one pair of which with the slide piece *h* is seen in Fig. 6, and their upper ends are enlarged into a hollow head, two notches being made in the cap *i'* over the said head on opposite sides (more clearly seen in Fig. 7). There are slits through the sides of the upper hollow part of the twisting rods as seen at *i''* and a corresponding slit through the bearing in piece *h*. When the twisting tube is in position to receive the strands to 70 be twisted as in Figs. 4 and 6, this slit has a cross cut at the bottom, so as to carry one of the threads to the opposite side from its entrance. On a level with the upper surface of the cap *i* there are guides or directing 75 shields *g*, affixed to the slide pieces *h*, the form of which is sufficiently shown in Figs. 6 and 7. They are for the purpose of properly directing the spring hoop when it is inserted. They stand out in a tangential 80 line and catching the end of the hoop as it is thrust forward bend it around, and guide it between the strands of the cord, the twisting rods *i* at that time being in the position seen in Fig. 7, with a strand on each side of the 85 spring, as indicated by the notches or holes in the cap *i'*. The twisting rods *i* extend down to bearings attached to the base.

The bearings are composed of a casting *k*, 90 which is a cross piece with two lugs projecting up from it, (most clearly seen in Fig. 1.) This piece is pivoted by its center to the base, as seen in Fig. 1. The lugs form bearings for another piece *k'*, through 95 which is a mortise, and at right angles to said mortise the twisting rod passes through the upper side of the piece *k'*, which thus forms a bearing for it and into a socket under the mortise in which its lower end rests. There is a pinion *i''* on the said twisting 100 rod within the mortise that gears into the spur wheel *b*, the gimbal joint thus formed allowing the upper end of the twisting rods 105 freedom to follow the curvers of the former while the pinions are kept properly in gear. 110

It is obvious that other mechanical arrangements can be here employed to effect

the purpose such as a universal joint in the twisting rods, but the above sufficiently explains the invention.

Within the twisting rods near their lower ends are flier formed spool carrier frames i^4 shown in Figs. 1 and 2, into which two or more spools i^5 are put on which the strands to form the cords are wound, (said cords being shown in red lines on the drawings). These strands are led up through the opening heretofore described in the rods i near their upper ends into the hollow center thereof and are there spread, one on each side of the cap i' , above which they are twisted together into a cord, as clearly shown in Fig. 6.

To produce the proper friction on the spools for the necessary and equal tension of the strands in delivering them therefrom, 20 I apply to the surface of the strands wound upon the stools a curved friction plate m (see Figs. 1 and 2) the two ends of which bear on the two spools i^5 , the center being drawn inward by a loop of india-rubber or 25 its equivalent affixed in the flier frame on the opposite side at n ; I find this arrangement efficient to produce an exactly equal strain upon the two spools aforesaid, whether there be more or less cord upon them and however 30 much their diameters may differ. It is obvious the exact form of the apparatus may be varied while it remains substantially the same its purpose being to produce exact equality of tension on the strands from both 35 spools under all circumstances.

The twisting rods are revolved by the large gear wheel b that is driven by gear pinions $b' b^2 b^3$, that connect it with shaft e .

The operation of making skirts by this 40 machine is as follows: The spools i^5 are put into the flier frames i^4 , with the friction apparatus m properly adjusted and the strands therefrom are led up through the slit i^2 in the upper end of the twisting rods, 45 which for this purpose are brought into the position shown in Figs. 4 and 6. With the slit i^2 opposite a similar slit in the piece h the two strands are then parted in the hollow head and brought into the notches on 50 the opposite sides of the cap i' . The ends of the strands are then brought together and affixed to a belt around the upper flanch c of the former or otherwise affixed at that point, the former at this time being in its 55 lowest position, as in Figs. 1 and 2, with the upper ends of the twisting rods near the said upper flanch c of the former. The twisting apparatus is then turned until a sufficient length of cord is twisted to receive 60 the first spring or hoop, the former being gradually raised by the cord c^2 in manner as before described, so as to keep the cords being formed extended properly. The twist-

ing rods are then turned so as to bring the caps i' into the position shown in Fig. 7, 65 with the notches in said caps on opposite sides of a circular line drawn through their centers, and thus cause a loop made by the strands to stand open, through which said circular line runs. The end of a spring is 70 then inserted between the first and second loops and being thrust forward is caught by the tangent guides g and bent inward and guided through the succeeding loops entirely around the circle. The spring being 75 thus inserted between all the strands, the twisting and elevating apparatus are again put in motion and another length of cord is twisted sufficient for the distance between the first and second springs. When the 80 twisting apparatus is again stopped in proper position and a second spring introduced in the same way as the first—when the twisting again commences. This is repeated until all the springs are inserted, and 85 the skirt is completed; the strands are then fastened at the lowest spring, the ends severed, the skirt removed, and the former lowered into its first position, when a second skirt is commenced, but in this case the 90 time and labor for inserting the strands into the twisters is saved, as they are continuously supplied from the spools until they are exhausted. This is an important improvement as a saving of time and labor 95 over my former machines.

Having thus fully described my improvements, what I claim as new, and desire to secure by Letters Patent, is—

1. The twisting apparatus constructed 100 substantially in the manner and for the purposes set forth, and consisting of a spool holder and tension apparatus as described, and strand guides, or head and cap, as herein described.

2. The head and cap i' as herein specified however combined in the manufacture of hoop skirts.

3. The tension apparatus and flier frame constructed and applied as herein set forth 110 in the manufacture of skirts by machinery.

4. The guides g , for guiding the springs or hoops into place in the manufacture of hoop skirts however made—so that a spring can be inserted by one end and pushed 115 around into place without being guided by hand into the curve all as above specified.

5. The employment of the elevating cord c^2 and drum d combined with the machinery for forming the spring skirts as herein 120 specified.

CAESAR NEUMANN.
